SLAB CONSTRUCTION

Clarke F. Davis, Short Hills, N. J., assignor to
 American Cyanamid & Chemical Corporation,
 New York, N. Y., a corporation of Delaware

Application May 4, 1936, Serial No. 77,687

6 Claims. (Cl. 72—68)

The present application is related to my co-pending application Serial No. 655,591.

The present invention relates to a deck construction using precast slabs.

5 The principal object of the invention is the provision of a floor or roof deck where the precast slabs constituting the deck are of a channelled type, which channel may be filled with any desired material.

10 Another object of the invention is to construct a deck as above, of precast slabs mated or joined together such as by tongues and grooves. It is particularly desirable to construct such slabs with metal edge members where the tongues and 15 grooves are constituted by portions of these members. Where desired, they may be further protected from below by fire-resisting material.

To this end, the invention contemplates a roof, 20 floor or other deck of precast slabs preferably, though not necessarily, carrying metal edge members, where the members on opposite edges of the slab are complementarily shaped. In some instances, these shapes may constitute tongues and grooves so that the adjacent edges of two slabs 25 will, through the medium of the metal members, form spaced apart I beams. Where desired, a channelled type of precast slab may be used, in which event it will be found desirable to fill the channel with cinders, cinder concrete, concrete, 30 gypsum, sound or heat insulation material or the like. Where the fill is placed in the channel in a wet condition, it will be found desirable to first waterproof the face of the channel to prevent absorption of the moisture by the slab itself and also to provide a weep-hole through which any 35 excess moisture either in the mix or accumulating in the channel as by rain or the like, may escape.

In some instances, it will be found desirable 40 to protect the metal members from below from the ravages of fire by special insulating material.

The invention further consists in the novel arrangement, combination and construction of parts more fully shown and described in the accompanying drawings.

In the drawings:

Fig. 1 is a plan view of the slab of this invention;

Fig. 2 is a partial plan view showing the manner of assembly of the slabs of Fig. 1 into a deck;

Fig. 3 is a sectional view along the line 3—3 of Fig. 2 with a filling and floor finish in place;

Fig. 4 is a view similar to Fig. 3 showing a modified form of floor finish and with soffits protecting 55 the metal edging;

Fig. 5 is an enlarged sectional detail showing the manner of attachment of the soffits and

Fig. 6 is a partial perspective view of the soffit itself.

Referring now with particularity to the drawings, there is shown in Fig. 1 a precast slab having a body 1 of set cementitious material such as gypsum or the like either with or without wood chips or other filling material, cast so as to form a channel 5 therein.

10 Complementary metal edge members are provided on at least two opposite edges of the slab and these may consist of webs 2 and lower and upper flanges 3 and 4 respectively. As shown, the flanges 3 are completely embedded in the body 15 material 1, while the flanges 4 lie substantially flush with one face of the slab. The end portions of both the flanges 3 and 4 are turned back into the slab as this makes for a sturdier construction.

It will also be apparent that the webs 2 in the 20 complementary members are provided with tongues and grooves so that when the two are placed together, one meshes or mates with the other and forms a substantial I beam.

Where desired, a reinforcing mesh 6 may be 25 provided and it has been found to be particularly efficacious if the ends of this reinforcing mesh rest at one end on top of the groove and at the other side, inside of the tongue as shown in Fig. 5.

Similarly, complementary metal members may 30 be provided on the short edges of the slab as well.

In erection, a deck may be formed as in Fig. 2 by placing together a series of the slabs shown in Fig. 1, it being preferable to stagger the joints between slabs as this makes for a stronger construction.

35 In Fig. 3, a deck has been shown made of the slabs of Fig. 1 assembled in the manner of Fig. 2 where the channel 5 has been filled as at 49 with some material, such as dry cinders, cinder concrete, concrete, gypsum or any other filling material wet or dry which may or may not have heat and sound insulating properties. Where concrete is used, a particularly strong deck construction results due to the fact that in addition to the 45 spaced apart I beams formed by the mated metal members, the set concrete forms spaced apart beams.

40 Where a wet fill such as concrete or the like is used, it may be desirable before the same is poured into the channel to surface the inside of the channel with a waterproof coating such as asphaltum, paint, metal foil, or the like. This coating is shown diagrammatically at 51. It 50 may also be desirable to provide a weep-hole 52 55

at the bottom of the slabs so as to permit excess water either incorporated in the fill or which may collect in the channel from rain during the construction operation to escape.

Obviously any type of floor finish may be applied directly over the tops of the slabs and in Fig. 3, this is shown at 50 to consist of an ordinary wood flooring while in Fig. 5 the floor 53 is shown of concrete or other plastic material poured directly on top of the fill 49. The use of an additional floor material materially assists in load distribution.

It will be understood, of course, that it is not necessary to apply a fill to the channel 5 and in this event where a floor 50 or 53 is applied to the slabs, the space of the channel serves the purpose of insulation.

In order to protect the flanges 3 of the metal members from the ravages of fire which might exist below such a deck, it may be desirable to provide special soffits of greater fire-resisting material such as asbestos, concrete or the like. These soffits are shown in Fig. 6 to consist of a body material 54 into which is embedded a member 55 adapted to be received between the webs 2 of the metal members. In Fig. 4, the part 55 is shown as terminating short of the tongue and groove, while in Fig. 5 the part 55 extends beyond and conforms to the tongue and groove. In the former case, it may be desirable to apply nails 56 or the like to apertures 57 to assist in maintaining the soffit in place, although in the form shown in Fig. 5, this will not be necessary. In all cases, appropriate areas of the adjoining slabs will be cut away in order to accommodate the soffit in order to maintain the flat continuity of the under face of the slabs. Any type of ceiling finish may be applied direct to the under face of these slabs.

While the invention has been shown and described with particular reference to specific embodiments, it is to be understood that it is not to be limited thereto but is to be construed broadly and restricted only by the scope of the claims.

I claim:

1. A building construction comprising a series of contiguous precast slabs having mated edges, each of said slabs having a longitudinal channel in its upper face, each channel being faced with waterproofing material, with a filling in the channel and a finish material overlying the slab and fill.

2. A building construction comprising a series of contiguous precast slabs having mated edges, each of said slabs having a longitudinal channel in its upper face, and a fill in said channel in which the mating edges of the slabs are constituted by metal tongued and grooved members. 5

3. A building construction comprising a series of contiguous precast slabs having mated edges, each of said slabs having a longitudinal channel in its upper face, and a fill in said channel in which the mating edges of the slabs are constituted by metal tongued and grooved members with a soffit beneath the mated metal members, the body of the soffit being of greater fire resistivity than the body of the slab. 10

4. A building construction comprising a series of contiguous precast slabs having mated edges, each of said slabs having a longitudinal channel in its upper face, and a fill in said channel in which the mating edges of the slabs are constituted by metal tongued and grooved members with a soffit beneath the mated metal members, the body of the soffit being of greater fire resistivity than the body of the slab, the bottom of said soffit being flush with the bottom of the 25 slabs. 20

5. A building construction comprising a series of contiguous precast slabs having mated edges, each of said slabs having a longitudinal channel in its upper face, and a fill in said channel in which the mating edges of the slabs are constituted by metal tongued and grooved members with a soffit beneath the mated metal members, the body of the soffit being of greater fire resistivity than the body of the slab, and holding 30 means carried by the soffit extending into the joint between slabs. 35

6. A building construction comprising a series of contiguous precast slabs having mated edges, each of said slabs having a longitudinal channel in its upper face, and a fill in said channel in which the mating edges of the slabs are constituted by metal tongued and grooved members with a soffit beneath the mated metal members, the body of the soffit being of greater fire resistivity than the body of the slab, and holding 40 means carried by the soffit and extending into the joint between slabs and conforming closely to the tongue and groove of the slabs. 45
